Term of patent 14 years

(Cl. D81—10)

Fig. 1.

Fig. 2.

Fig. 3.

Fig. 1 is a side elevation of a charcoal grill embodying my new design;

Fig. 2 is an end elevation thereof; and

Fig. 3 is a top plan view thereof.

The other side and end, not shown, are like the respective side and end as shown in Figs. 1 and 2.

The essential features of my design reside in the portions shown in full lines.

I claim:

The ornamental design for a charcoal grill or the like, as shown and described.
